(57) **CLAIM**

The ornamental design for a water purifier, as shown and described.

DESCRIPTION

1. Water purifier

1.1 : Front

1.2 : Back

1.3 : Left

1.4 : Top

1.5 : Bottom

1.6 : Perspective

1.7 : Perspective

1.1 is a front elevation view of a water purifier showing our new design; 1.2 is a back elevation view thereof; 1.3 is a left side elevation view thereof, while the right side elevation view thereof is symmetrical with the left side elevation view and is thereby omitted; 1.4 is a top plan view thereof; 1.5 is a bottom plan view thereof; 1.6 and 1.7 are two perspective views thereof; the water purifier is mainly used for purification and filtration of water.

1 Claim, 7 Drawing Sheets
